DENTAL IMPRESSION TRAY

Clifford A. Fisher and June A. Fisher, Silver Spring, Md.

Application March 18, 1955, Serial No. 495,152

5 Claims. (Cl. 32—17)

This invention relates to dental instruments or accessories and pertains more particularly to a dental impression tray of improved form which is most advantageously adapted for use with so-called colloid type impression compounds.

Colloid compounds are readied for use by mixing together, in the presence of a suitable solvent, two mixtures which may be in powder form or otherwise and the resultant compound is characterized by its high degree of fluidity and stickiness which presents some difficulty in retaining the mass of compound within the confines of the tray and in maintaining the mass in proper shape while in the tray. It is, therefore, a primary object of this invention to provide an improved form of dental impression tray for use with colloid type compound wherein provision is made for not only retaining the mass of compound within the confines of the tray but also for maintaining the mass in proper shaped relation while in the tray.

A further object of this invention is to provide an improved impression tray having a handle means thereon for aiding in the manipulation and placement of the tray within a patient's mouth.

Another object of this invention lies in an improved dental tray so preformed and preshaped as to readily conform to the contour of a patient's jaw, the tray being readily made in a minimum number of basic shapes and sizes so that the tray may be used in either the upper or lower jaw areas and in either the front or back portions of the mouth.

Still another object of this invention resides in an improved form of dental tray having a base and upstanding opposite side walls such that the tray is open at its opposite ends and wherein means in the form of a rolled or solid bead around the edge of the tray is provided for the purpose of maintaining the proper shape of the impression compound mass within the tray.

A further object of this invention is to provide an improved dental tray having a base and upstanding opposite side walls such that the tray is open at its opposite ends and wherein the metallic material from which the tray is made is perforate throughout its area to allow the impression compound material to extrude partially therethrough whereby the compound will have interlocking engagement with the tray.

Another object of this invention resides in the provision of an improved dental tray having a handle pivotally attached thereto so that the tray may be easily and effectively maneuvered within the patient's mouth to place the tray in proper position therein.

With the above and other objects in view, the invention consists in the construction and novel combination and arrangement of parts hereinafter fully described, illustrated in the accompanying drawings and pointed out in the claims hereto appended, it being understood that various changes in the form, proportions, and minor details of construction, within the scope of the claims, may be re-

2

sorted to without departing from the spirit or sacrificing any of the advantages of the invention.

In the drawings:

Fig. 1 is a perspective view showing the improved dental tray in use;

Fig. 2 is a top plan view of the improved tray;

Fig. 3 is a side elevation view of the tray showing the same filled with a mass of compound and illustrating the assembly in use;

10 Fig. 4 is a transverse sectional view through the tray showing the pivotal mounting for the handle; and

Fig. 5 is a top plan view of a modified form of tray showing various positions of the handle in dotted lines.

Referring now more particularly to Fig. 1, the dental tray is indicated generally by the reference character 10 and preferably takes the form of a main body or tray portion 11 and a handle means 12 pivotally attached thereto.

Figs. 2—4 more clearly illustrate the details of construction and reference is had at this time thereto. Fig. 2 most clearly shows the base 13 of the tray which is elongate and which is bounded on opposite sides by a pair of upstanding walls 14 and 15. The base may be formed so as to be substantially straight or it may be formed as in Fig. 2 with a longitudinal curvature. In the former case, the tray is particularly adapted to be used in the molar region where the teeth are very nearly arranged in a straight line whereas in the latter case as shown in Fig. 2, the tray is adapted for use in the front curved portion of the mouth. It will be appreciated that only two or three trays having different radii of curvature will be sufficient to properly fit any patient's mouth.

The sidewalls 14 and 15 are preferably slightly inclined to the vertical so that they are upwardly divergent and will more readily and comfortably conform to the natural contours of the mouth. The base 13 is substantially flat and the side walls 14 and 15 form therewith an open ended trough.

The tray is preferably formed from a non-corrosive metal such as stainless steel or the like and the entire area thereof is provided with a plurality of openings or perforations 16. These perforations need not be patterned in any specific manner, it being only necessary that a sufficient number of them be provided to allow the fluid mass M of rubber base colloid compound to partially extrude therethrough and form an interlocked engagement with the tray. The protuberances or nipples formed by the compound flowing or extruding through the perforations is indicated by the numeral 17 as shown most clearly in Fig. 3.

The upper corners of the side walls are curved to provide smooth contours and merge smoothly with the opposite ends of the base and the marginal edge portions 55 of the side walls and the ends of the base are rolled inwardly to form the continuous bead 18. This bead forms a barrier all around the tray which is substantially perpendicular at all points to the adjacent surface and serves to retain the fluid mass M of compound within the confines of the tray. Also, this bead presents a smooth edge

60 which will obviate cutting or bruising of the patient's gums, tongue or mouth. In practice the bead, although it is not of large size, will to a great extent prevent the compound from oozing over the edges of the tray, particularly as this will tend to happen when the impression is being made.

The compound when set is a resilient, rubber-like mass which, although it may be deformed, will spring back to its original shape and so produce a permanent impression record. Thus, it can be seen that the hardened or set compound is easily removed by hand from the tray

even though the nipples 17 protrude through the various openings 16.

The handle 12 provides a very advantageous means for manipulating and positioning the tray within a patient's mouth, it being possible to rotate the handle a full 360 degrees with respect to the tray. Thus, when an impression is being made of the front portion of the mouth, the handle 12 will be disposed more or less perpendicular to the longitudinal axis of the tray whereas when the impression is being made at or near the rear of the mouth, the handle will most advantageously assume a position more or less parallel with the longitudinal axis of the tray.

The handle is provided adjacent its free end with an opening 19 so that the assembly may be conveniently suspended from a hook while not in use and the opposite end thereof is provided with the opening 20 aligned with an opening 21 in the base 13 to receive therethrough the stem 22 of a rivet or the like fastener. The rivet as shown most clearly in Fig. 4 has its head 23 disposed lowermost and with its uppermost end 24 upset or headed over. The net result is to freely pivotally secure one end of the handle 12 to the undersurface of base 13.

The area of the base 13 immediately adjacent and surrounding the rivet is preferably free of apertures 16 to allow substantial swinging movement of the handle 12 without the handle encountering any of the nipples 17 of compound which are extruded through the perforations 16.

Of course, the side walls 14 and 15 are so shaped as to most nearly approximate the normal mouth contours and to this end, the side wall 14 as shown in Fig. 2 is inwardly dished in the region 25 to conform with the natural curvature of the inner side of the gums since the impression tray shown in Fig. 2 is always to be used with the side wall 15 outermost.

The modification shown in Fig. 5 is similar to that described above but differs therefrom in the formation of the bead 26. In this case, the bead is so formed as to present a continuous water tight passageway all around the tray. This may be accomplished by any suitable means such as soldering the free edge of the bead to the adjacent surface of the tray, by affixing a length of tubing around the edge of the tray, or otherwise, as desired. In any case, the passageway is provided with inlet and outlet spigots 27 and 28 projecting substantially longitudinally from the tray so that lengths of flexible supply and discharge hose may be engaged thereover and through which cooling medium may be circulated through the passageway. The cooling effect materially enhances and accelerates the setting action of the compound. To assure that the cooling medium will travel throughout the length of the bead passageway, a dam 29 is placed between the inlet and outlet 27 and 28.

The dotted line positions of the handle 12 in Fig. 5 serve to illustrate some of the positions in which the handle may be disposed.

Although we have shown specifically a pivoted handle attached to the tray, it is of course possible to maneuver the tray within a patient's mouth with some degree of success by using a handle which is rigidly attached to the impression tray.

We have shown by way of example an impression tray for use in taking impressions of a part of the jaw. However, it is to be understood that the invention may be used on a tray for taking an impression of the full jaw or any part thereof.

We claim:

1. In an impression tray comprising a body of curved formation on a longitudinal plane, the body having a base, upstanding side walls and open ends, the base and side walls having perforations therein, the side walls and the ends of the base having a means thereon to hold impression material within the tray with the impression material entering the perforations and being locked to the tray, and handle means carried by the body.

2. The impression tray as defined in and by claim 1, wherein the means on the side walls and the ends of the base is a rolled bead formed integrally with the side walls and the base.

3. The impression tray as defined in and by claim 1, wherein the body is of a U-shaped construction with the legs being the side walls and the base of the body being the base of the U-shaped construction.

4. The impression tray as defined in and by claim 3, wherein the legs of the U-shaped construction have a rolled bead along their free edges and the base of the U-shaped construction has a rolled bead along its ends, the rolled beads of each part being connected to form a continuous rolled bead throughout the entire free edge of the body of the tray.

5. A dental impression tray comprising a body having a substantially flat base and upwardly divergent side walls on opposite sides thereof, an inwardly rolled continuous bead along the free edges of said side walls and the opposite ends of the base, an elongate handle having one end underlying a central portion of the base, means projecting through said one end of the handle and the central portion of the base and pivotally interconnecting the same, said body being provided with perforations throughout its area.
